STAMPING AND EMBOSsing MACHINE

Joseph J. Weber, Chicago, Ill.

Application December 22, 1947, Serial No. 793,155

2 Claims. (Cl. 41—7)

1

In general this invention relates to machines for stamping out forms, letters, or characters, from ribbons of gold, silver, or such other suitable material, and transferring them onto various kinds of articles such as leather goods, plastic material, or such other material as may be capable of receiving impressions pressed from such ribbons, but more particularly the invention relates to improvements in automatically operated stamping and embossing machines in which is provided mechanism for automatically propelling the above-mentioned kind of ribbon forward for each successive return or upstroke of the stamp or type carrying ram after each imprinting or stamping operation has been performed.

The invention further contemplates not only the provision of such mechanism having the above-stated characteristics, but also the provision of the rotation of the imprinting forms holder about the axis of the ram to various desired horizontal angular positions whereby impressions may be made diagonally upon an article without necessarily having to move the same from its position of adjustment.

The invention further contemplates the provision of mechanism for not only automatically propelling the kind of ribbon above-mentioned forward in such lengths as may be desired in each successive up-stroke of the type-holder carrying ram carrying the imprinting forms preparatory for making the next or succeeding impression, but also provides for rotating the type-holder about the axis of the ram to various desired horizontal angular positions whereby impressions may be made diagonally upon an article without necessarily having to alter the article materially from its original position as installed under the type.

The invention further contemplates the provision of adjustable mechanism for causing the above-mentioned kind of ribbon to be propelled in various lengths in each up-stroke of the ram preparatory for making the next or succeeding impression, notwithstanding to what horizontal angular position the type-holder carrying the type or stamp may be arranged about the axis of the ram.

The invention also contemplates a simple adjustable device, which forms a portion of the ribbon propelling mechanism, to be so adjusted as to cause the said propelling mechanism to propel a ribbon of the kind above-mentioned, or it may be a typewriter ribbon, forward in each up-stroke of the type carrying ram in any desired length regardless of what horizontal angu-

2

lar position the said type-holder may have been arranged about the axis of the ram.

The invention also contemplates the automatic operation of the above-mentioned ram by fluid pressure means as shown, or electrically, as, for instance, by means of a solenoid, not shown.

The invention also contemplates the provision of an adjustable open or built-up frame supported by a platform upon which to arrange the goods or material to be printed or stamped, and for adjustably supporting a guide by which to support a printing or stamping fluid pressure operated ram and its accompanying fluid cylinder. And further, the invention contemplates, as above-stated, the provision of an adjustable framework of open construction whereby that portion thereof which supports the ram guide and the said cylinder may be so adjusted as to increase or decrease the distance between the type-holder and the work to be printed or stamped. Also, the invention contemplates the provision of a ram which may be adapted to support a holder for holding an arrangement of type or stamps, and for supporting a chase in which a printing form may be arranged. It also contemplates an open or built-up frame which is adapted to support at various stages, said ram and the type supported thereby to the extent that when stamping or embossing is being performed a uniform and even impression of the type or form is being made upon the work being supported by an adjustable platform supported by the said frame.

These and other features contemplated in the invention may be better understood by referring to the several illustrations in the accompanying drawings, and more fully described in the following specification, and more particularly pointed out in the appended claims.

Illustrated in the accompanying drawings:

Figure 1 is a front view of the invention embodying the improvements as contained therein, and shows the type-holder carrying ram in its uppermost or inoperative position;

Figure 2 is a side or end view of Figure 1, with certain portions of the ribbon feeding or take-up mechanism not being shown;

Figure 3 is a sectional view as seen from the plane 3—3, of Figures 1 and 2, but not showing the ribbon take-up rolls nor the ribbon-roll arbor;

Figure 4 is a front view of a portion of the type-holder mechanism showing how the same may be altered to support a chase in which a printing form may be arranged;

Figure 5 is a sectional view as seen from the plane 5—5, of Figure 4;

Figure 6 is an enlarged sectional view of the type-holder locking mechanism as seen from the plane 6—6, of Figure 2;

Figure 7 is a top plan view of Figures 1 and 2; and

Figure 8 is a sectional view taken on the plane 8—8, of Figure 2.

Throughout the several views similar characters refer to similar parts.

Essentially, the invention comprises an open or built-up adjustable frame in which is supported the printing and stamping mechanism. As illustrated in the accompanying drawings, the above-mentioned frame comprises a lower or base plate 13, and an upper plate 11; the same being adjustably supported by uprights, 12 and 12'. In turn plate 11 supports a guide 13, through which a type-holder carrying ram 14 operates. Being supported by said plate 11, by means of uprights 15, which are rigidly secured in plate 11, is a pneumatic or hydraulic cylinder 16, in which operates a piston 17, to which is connected the upper end of type-holder carrier ram 14. The cylinder 16 is provided with a cylinder head 19, at its upper end which is supported by uprights 15, and there securely fastened by means of nuts 19', as shown. And at the lower end of said cylinder is provided packing means for sealing piston rod 17', as is shown at 16', and 16''. Pipe connections are made in the wall of the cylinder, as at 18, and to the cylinder head 19, as at 20, through which pneumatic or hydraulic pressure may be forced against, either above, or beneath, the piston 17, to cause the same to operate downwardly or upwardly as may be necessary to cause the type-holder 21, with whatever arrangement of type may be secured therein, to move to or from the work to be printed or stamped, or which has received the imprint or impression, as the case may be.

Referring to Figures 1 and 2, it will be seen that the type-holder 21 is hingedly secured to a horizontally revoluble bracket 22, by means of hinge-pin 23. The bracket 22, in turn, is revolvably mounted on the lower end of ram 14, and supported by means of a screw-threaded shouldered rod 24, being securely fastened, as by means of a dowel 25, to the lower end 14' of ram 14. Referring particularly to Figure 2, it will be seen that bracket 22 may be rigidly secured, as by means of a knurled set-screw 26, in any desired horizontal angular position which, incidentally, also positions the type-holder to such position of horizontal angular adjustment.

The type-holder 21, being, as above-stated, hingedly mounted on pin 23, may be swung from its printing or stamping position, as is shown in Figure 2, to its type-loading position, as represented by light dotted lines 21', and there locked in place by means of the locking mechanism, generally indicated by the reference character 26'. In the locking mechanism, locking pin 27 is adapted to lockingly engage holes, respectively, 28 and 29, depending whether the type-holder is in its printing or stamping position, or in its type loading position.

Referring to Figure 1, will be seen type or stamp clamping jaws 30, which are slideably mounted on a jaw retaining bar 31, and a right and left hand screw-threaded jaw clamping screw 32. To each end of screw 32, is fastened, as by means of key pin 33, a screw-operating handle or knob 34.

Referring to Figures 4 and 5, it will be seen that

the type-holder 21, and the jaws for supporting a chase and represented by the reference character 30', are made suitably larger than those, respectively, 21, and 30, the jaws being cut out as shown at 30'', to provide a ledge 35, upon which a chase may be supported.

Rigidly secured to the back of 22, as by means of screws 37, is a bracket 38, to which is mounted, at its left hand end, a flanged stud 38, upon which is mounted a spring-actuated friction disc 39, and a knurled screw-threaded nut 40, for backing up disc operating spring 41. At the right hand end of bracket 38, is mounted for rotation a take-up or feed roller 42, and securely fastened to said roller is the smaller, 43, of two sprocket wheels. The larger sprocket wheel, 44, is revolvably mounted on a shaft 45, and is directly in line with said wheel 43. A sprocket chain 46 connects the said sprocket wheels to each other, the larger sprocket wheel 44 being the driver, and the smaller wheel 43 being driven by the larger wheel 44, through the medium of the sprocket chain 46. Also, revolvably mounted on shaft 45, is a ratchet wheel 47, to which is secured, by means of key pin 48', a rack or spur gear 48. The sprocket wheel 44 is provided with a spring actuated pawl 49, hingedly mounted on a shouldered screw 50, the said pawl being adapted to engage said ratchet wheel 47. The shaft 45 is securely fastened, by means of a set-screw 45', in a bracket 51 which is fastened, by means of screws 52, to bracket 38. Engaging said gear 48 is a gear rack 53, the bracket 51 providing a guide for the rack 53. The upper end 53' of rack 53 is driven into an externally screw-threaded sleeve 54, the two being pinned together by means of key-pin 55. Threaded over screw-threads 54', of sleeve 54, is a knurled sleeve 56, which is adapted to be adjusted upwardly, or downwardly, as the case may require, to vary the travel of rack 53, which is operably connected, by means of said chain 46, to the said ribbon feed or take-up roller 42. Beneath sleeve 56 is provided a lock-nut 57, by which to lock said sleeve 56 in its desired position of adjustment. Between nut 57 and bracket 51, and over rack 53, is disposed a compression spring 58, which is adapted to automatically maintain said rack and ribbon feeding mechanism in such position of adjustment as will cause the desired length or amount of ribbon to be propelled by the said feeding mechanism. As will be noted in Figure 3, ram guide 13 is provided with radial flanges, respectively, 13' and 13''. The upper flange 13' is secured to plate 11, by bolts 9, but the lower flange 13'' provides a stop for the rack adjusting mechanism, or sleeve 56, regardless of what horizontal angular position the type-holder mechanism may have been adjusted to. The lower end of the rack is provided with a stop or limit pin 59. The ram 14 is also provided with a stop or limit pin 60, which assures the ram 14 of not going beyond its upward limit of stroke.

About equidistant from either side of the center-line of the machine (front view) are ribbon guides 61, adjustably mounted on outstanding rods 62, which are fastened securely in slidingly mounted spring actuated rod supports 63, being inclinedly and adjustably mounted on bracket arms 36'. The guides 61, between which ribbon "R" may be guided, may be adjustably secured on rod 62, either by friction or a set-screw 64, as shown.

Supports 63 are slidingly mounted between the face side of arms 36' and washers 65, which are held in place by means of cotter pins 66, through

posts or guides 67 and 68, which are securely fastened into arms 36'. A post 69 is securely fastened in the upper end of each of supports 63, and extending from post 69 is a tension spring 70, which is fastened to post 68. The spring 70 provides only a sufficient amount of tension to maintain a desired tautness of the above-mentioned ribbon which may be stretched across the face of types of a stamp.

Referring to the several views, Figures 1, 2, 3, and 5, it will be seen that the type-holder 21, the top 21', and back 21'', of which, form a right-angle with each other. And to the ends thereof is secured, as by means of screws 71 and dowels 72, end plates 73. And to the end plates 73 is fastened, as by means of screws 74 and dowels 75, the clamping jaw support and guide 31.

It may be here stated, that heating units are generally provided for heating the type or stamp in the holder in machines of the above description, but since it does not form a part of this invention any further mention is not made.

The type-holder 21, as previously stated, is hingedly mounted on hinge-pin 23, which is forcibly pressed into openings 23', in portions, respectively, 22' and 22'', of bracket 22.

As previously stated, plate 11 and the mechanism supported thereby, is adjustably supported by the uprights 12 and 12'.

The lower upright 12 is forcibly pressed into plate 10, at the four opposite corners thereof and there flush-riveted into place squarely with plate 10. Further, upright 12 is internally screw-threaded with screw threads 12'', which correspond to screw threads 12''', formed on the upright 12'. In this instance, upright 12' is provided with an enlarged portion 76, which provides a shoulder 76', upon which to support plate 11. In each of the opposite corners of plate 11, are provided identical circular openings 77. Through each of said openings is extended a reduced circular portion 78, of upright 12'. The said portion 78, revolvably, but closely, fits said opening 77, and is constructed slightly shorter than the thickness of plate 11. Extending up from portion 78 is a short circular portion 79, over which is fitted a washer 80. And, extending up from said portion 79 is a reduced circular portion 81, the same being of suitable diameter to snugly fit the bore provided in gear wheel 82, and to come flush with the face 82'' of hub 82', of wheel 82. A keyway should be cut in extension 81, to match the keyway provided in wheel 82, and a key 83 provided therefor. Between the face 82'' and a washer 84, is placed a spring washer 85. Extending up from portion 81 is a screw-threaded portion 86, over which is threaded a nut 87, with which to draw the several parts, 76, 11, 80, 82, 83, and 84, in close frictional working relation to each other. Uprights 12' are each provided with a locknut 8, with which to lock uprights 12 and 12' securely together.

Each upright 12' is provided with wheel 82, and in mesh with each wheel 82 is a worm 88, which is fastened, as by a key pin 88', to a shaft 89, the same being journaled in bearings 90. And to corresponding ends of shafts 89 is fastened, as by a key pin 91', a sprocket wheel 91, the same being connected to each other by means of a sprocket chain 92. To the opposite corresponding ends of shafts 89 is secured, by means of key pin 93, hand wheel 94, by means of which shafts 89 may be operated through the medium of this connecting sprocket chain 92. On desiring to raise or lower plate 11 and the imprinting and

stamping mechanism associated therewith, it will only be necessary to operate hand wheel 94 in the desired direction, which, in turn, operates upright 12', through the medium of worm 88 and wheel 82. Shafts 89, as stated, are journaled in bearings 90, the same being secured to plate 11, as shown, by means of screws 90'.

It may be here stated, that in some instances, a special platform (not shown) may be arranged below the type or stamp, and supported by plate 10, whereupon some special imprinting or stamping operation may be required to be done upon some special article. Generally, however, most imprinting and stamping operations may be done upon articles being directly supported upon a raised platform 10', supported by plate 10.

Before beginning imprinting or stamping operations, the ram, carrying the type-holder, is raised to its uppermost position either by pneumatic or hydraulic pressure applied to the underside of piston 17, and there held, by means of the pressure, while the type, or the form in the chase, is being arranged and clamped between their respective clamping jaws, 30, or 30', as the case may be. In order to be better able to arrange the type, or chase, between their respective clamping jaws, it only will be necessary to place type-holder 21 in the position indicated by light dotted lines, as is shown in Figure 2.

To place the holder in said indicated position it will be first necessary to unlock locking mechanism 26' from its locked position, by taking hold of locking pin 27, operating lever 21', and move said pin 27 from engagement with said hole 28, and with the lever swing the holder 21, until locking pin 27, becomes in engagement with the hole 29.

As will be seen by referring to Figure 6, and Figures 1 and 2, lever 21' is hingedly mounted between ears or lugs 96, on pin 97, secured in said lugs, the said lugs being formed on said holder. And, when the type has been properly arranged, or a chase having a form disposed therein has been clamped between respective jaws, the type-holder may again, by taking hold of lever 21', remove locking pin 27 from engagement with hole 29, swing the type-holder to its former or imprinting or stamping position and there locked in place by allowing pin 27, to again engage hole 28. As will be seen by referring to sectional view, Figure 6, lever 21' engages pin 27, through a slot 27'' formed therein. In order to be assured of pin 27 remaining in either of its locked positions in engagement with said holes 28 or 29, the same is held in said locked positions, until removed from engagement with said holes by means of said lever 21', by means of a spring 98, acting against a shouldered pin 99, which is mounted in a guide 100, secured, as by means of screw-threads 100', threaded into a screw threaded hole 100'', formed in that portion of the type-holder which supports lever 21'. The said pin 99 is, in turn, secured to a piece 101, as by means of key pin 101', which is, in turn, fastened to the upper end of pin 27, by means of a machine screw 102, as shown.

As previously stated, nut 56 may be adjusted upwardly or downwardly to provide a longer or shorter movement of rack 53, as the case may require, to cause the ribbon feeding or propelling mechanism to feed the ribbon in longer or shorter lengths as may be required. And, it may be necessary to adjust plate 11, which carries the printing mechanism, upwardly, or downwardly, to bring the type to a position to suit the article

upon which imprinting or stamping is to be done. As it may become necessary to adjust plate 11, to cause it to be raised or lowered, it will only be necessary to revolve hand-wheel 94, in the direction to cause plate 11 to be moved upwardly, or downwardly, as may be required to bring the type into proper relation with the article upon which imprinting or stamping is to be done.

It may be here stated too, that it has been found that imprinting and stamping machines having the type or chase holder carrying ram disposed at the end of an arm extending out from a vertical column an even and uniform impression will not result in view of the fact that when imprints or impressions are being made in such machines, there is the tendency of the outstanding arm to deflect from its normal horizontal position which results in an uneven and unsatisfactory imprint or impression especially when great pressures are required to make certain impressing and embossing operations. To obviate this unsatisfactory imprinting result the type or chase holder carrying ram is supported centrally between four uprights or corner posts forming a portion of the open framework described above. Also, as will be seen by referring to Figure 2, the top surface 21''' of holder 21 is in engagement with the undersurface 22''' of bracket 22, when the holder 21 is arranged in its locked imprinting or stamping position. Therefore, the holder being so arranged against the bracket 22 actually forms a joined continuation of the ram 14 together with bracket 22; therefore, any pressure exerted against the ram will be direct and uniformly distributed upon the type or stamp being arranged in the holder in view of the fact that the same are, substantially, uniformly arranged about the longitudinal center-line of the ram.

Having thus described the invention it may be readily understood that the minor details of its construction may be altered in several ways without departing from the spirit and scope of the invention, and without losing any of its attendant advantages. Therefore, what is claimed is de- sired to be secured by Letters Patent.

I claim:

1. In combination, a compressed fluid operated stamping and embossing machine embodying an upwardly and downwardly adjustable skeleton frame-work having a pressure controlled fluid

operated motor centrally installed therein, and, horizontally revoluble imprinting and embossing devices holder operably controlled by the said motor, mechanism adapted to releasably lock said holder in a type or stamp loading position and in a stamping position comprising a spring actuated locking pin operably controlled by a hand operated lever, and ribbon foil carrying and operating mechanism carried by the said holder.

2. In combination, a compressed fluid operated stamping and embossing machine embodying an upwardly and downwardly adjustable skeleton frame-work having a centrally disposed pressure controlled fluid operated stamp holder operating motor having a nonrevoluble reciproable piston installed therein, a horizontally revoluble and hinged mounted stamp holder having ribbon foil carrying and operating mechanism mounted thereon operably controlled by the action of said motor piston, and mechanism arranged to releasably lock said holder in a type or stamp loading position and in a stamping position comprising a spring actuated manually controlled locking device, substantially as described.

JOSEPH J. WEBER.
